(57) **CLAIM**

I claim the ornamental design for a portable light, as shown and described.

DESCRIPTION

FIG. 1 is a perspective view of a portable light.

FIG. 2 is a front view of the portable light.

FIG. 3 is a rear view of the portable light.

FIG. 4 is a left view of the portable light.

FIG. 5 is a right view of the portable light.

FIG. 6 is a top view of the portable light; and,

FIG. 7 is a bottom view of the portable light.

The broken line showing represents portions of the article not claimed and forms no part of the claimed design.
